UNITED STATES PATENT OFFICE.

EDWARD POSSON, OF CHICAGO, ILLINOIS.

BRAKE MECHANISM FOR RAILWAY-CARS.

1,364,641.

Specification of Letters Patent.

Patented Jan. 4, 1921.

Application filed March 17, 1917. Serial No. 155,415.

To all whom it may concern:

Be it known that I, EDWARD POSSON, a citizen of the United States, residing at Chicago, in the county of Cook and State of Illinois, have invented certain new and useful Improvements in Brake Mechanism for Railway-Cars, of which the following is a specification.

This invention relates to improvements in the brake mechanism of railway cars, and its principal objects are to provide improved means for hanging and actuating the brake beams, and improved means for connecting the brake shoes to the brake beams. The invention is particularly adapted for brake systems in which the brake shoes clasp or grip the opposite sides of the car wheels, and are operated through a single system of mechanism extending to some convenient point on the car. An important feature is the provision of improved means for suspending the brake-operating levers in order to secure freedom of action of the levers, and to maintain a substantially parallel relation of the levers which actuate the brake shoes on opposite sides of a single car wheel. A further feature is the provision of means for hanging the brake beams in order to permit the necessary movement thereof while clearing the spring plank hangers and other parts of the structure of the car truck. Another important feature is the provision of improved means for supporting the brake shoes on the brake beams, and improved means for maintaining the brake shoes in their proper relation to the peripheral surfaces of the car wheels. Other objects relate to various features of construction and arrangement which will be set forth more fully hereinafter.

Various other objects of the invention and the means for accomplishing the same will appear from the following specification, taken in connection with the accompanying drawings, in which one embodiment of the invention is illustrated.

In the drawings—

Figure 1 is a side elevation of my improved brake mechanism, showing by dotted lines various parts of the car truck to which the present invention is applied.

Fig. 2 shows a perspective view of a bracket for the center lever-connecting carrier.

Fig. 3 shows a perspective view of one of

the suspending links or levers for the center lever-connecting carrier.

Fig. 4 shows a perspective view of a brake beam hanger.

Fig. 5 shows a perspective view of another form of brake beam hanger.

Fig. 6 shows a perspective view of the center lever-connecting carrier.

Fig. 7 shows an enlarged side elevation of a car wheel and part of the brake mechanism.

Fig. 8 is a partial end elevation of the car truck, and a partial section on the line 8—8 of Fig. 1, showing by dotted lines parts which are not embodied in the present invention.

Fig. 9 shows a top plan view of the brake mechanism, the car axles being indicated by dotted lines.

Fig. 10 shows a perspective view of a spring plank hanger.

Fig. 11 shows a perspective view of a brake hanger bracket.

Fig. 12 shows a perspective view of a brake beam key.

Fig. 13 shows a vertical section through a brake hanger, illustrating the connection of the brake shoe with the brake beam.

Fig. 14 shows a perspective view of the brake head adjusting connector.

Fig. 15 shows a perspective view of the brake head adjusting spring and bracket.

Fig. 16 shows a side elevation of a brake beam.

Fig. 17 shows an end elevation thereof; and

Fig. 18 shows a top plan view of the brake beam.

In the drawings the invention is illustrated as applied to a car truck, designated generally by the numeral 25, having a wooden frame.

This truck comprises side frame members 26 upon which are mounted the lever-carrying brackets 27, having the form illustrated particularly in Fig. 2, from

which it will be seen that the bracket comprises a flange 27^a directed inwardly and secured to the frame member by suitable bolts or rivets engaging the holes 28.

These brackets are located above the axles 29 of the car wheels 30, and the brackets above the central and inner wheels are of shorter length than the bracket 27 over the end wheel of the truck.

These brackets serve to support the brake mechanism, which comprises a plurality of suspending links or levers.

vers 31, pivotally connected to the hangers 27 by means of bolts 32 engaging the upper ends of the links 31, and suitable apertures 33 in the outwardly spaced, downwardly directed flanges 27^b of the brackets 27. Two of the links 31 are connected to each of the center brackets 27, and one is connected to the end bracket 27. The lower ends of the links 31 are inserted between and pivotally connected to complementary members 34^a of the center lever-connecting carriers 34, having the form illustrated particularly in Fig. 6. The links are pivotally connected to the lever carriers by means of suitable pins 35 engaging the links and suitable apertures 36 in the lever carriers, and these apertures are so located that the links 31, connected to the center brackets, will have a parallel relation.

20 A plurality of truck levers 40, which are indicated in Fig. 1 by the numerals 40^a, 40^b, 40^c, 40^d, 40^e, and 40^f, are mounted between the members 34^a of the lever carriers, and pivotally connected to the ends thereof at intermediate points on the levers by means 25 of pins 41. The upper end of the innermost truck lever 40^a is pivotally connected to an operating link or rod 42 which extends to suitable brake-operating mechanism located 30 at a suitable place on the car, and the upper ends of the levers 40^b—40^e, and 40^d—40^e are pivotally connected by means of the connecting rods 43 and 44, respectively. The upper end of the truck lever 40^f, at the end of the 35 truck, is pivotally connected to the downwardly-directed flange of the end bracket 27.

It will be apparent that the arrangement is such that the two truck levers 40 adjacent each car wheel are substantially parallel.

40 The lower ends of these truck levers are pivotally connected to the brake beams carrying the brake shoes, so that when the connecting rod 42 is actuated the motion is transmitted through the truck levers and 45 their hangers to all of the brake shoes, which are thereby moved into or out of engagement with the peripheries of the car wheels in a manner to be hereinafter more fully explained.

50 Before discussing further the operation of the brake lever mechanism, I will describe the means by which the brake shoes and brake beams are mounted. The side frames of the truck have projecting outwardly 55 therefrom the arms 45, which are connected by pins 46 with the spring plank hangers or brackets 47, as shown particularly in Figs. 7 and 8. These pivoted brackets carry shoes 47^a having rounded upper surfaces upon 60 which the spring planks 48 are adapted to rock. The springs 49 are mounted on the spring planks according to the modern method of car construction. Hanger brackets 51, having the form shown particularly 65 in Fig. 11, are secured to transverse frame

members 50 of the car truck, those on the inner sides of the end wheels of the truck being directed downwardly, while those on opposite sides of the center wheel of the truck are directed upwardly. The parallel 70 ears 51^a of these brackets are apertured, and are pivotally connected to brake hangers.

The brake hangers 52, on opposite sides of the center wheel, have the form shown in Fig. 4, and the brake hangers 53, adjacent 75 the end wheels of the truck, have the form shown in Fig. 5. It will be seen that the brake hangers 52 are offset, as shown at 52^a, in order to clear the transverse frame members of the car truck, and they are of greater 80 length than the hangers 53, owing to the necessary location of the brackets 51, caused by the construction of the truck. The hangers 53 at the ends of the truck are suspended from suitable supporting members 54 passing 85 through the end frame members 55 of the truck. The lower ends of the hangers are provided with cylindrical bearing members 56 which are adapted to be rotatably engaged by the cylindrical parts 57 of the brake 90 beams 58. The central parts of the brake beams have rectangular cross sections, as illustrated in Figs. 16, 17, and 18, and each brake beam carries at its opposite ends cylindrical parts 57, which terminate in parts 95 59 of reduced diameter having annular grooves 60 formed therein adjacent their extremities. The parts 56 of the brake hangers rotatably engage the parts 57 of the 100 brake beams, and thus permit a free movement thereof toward or away from the wheels which movement is effected through the lever mechanism previously described. The truck levers are connected to the brake beams by means of the truck lever connectors 62, having enlarged bearing members 62^a at one end which are keyed to the brake beams 58, and having apertures 62^b at the other end which are pivotally connected to the truck levers 40. By providing a plurality of apertures 62^b it is possible to change 105 the connectors on the truck levers in order to vary the positions of the paths of travel of the brake shoes and brake beams. It will be seen that the parts 57 of the brake beams 110 are provided with key-ways 57^a to permit a rigid connection with the members 62, and these key-ways serve also to permit the formation of a fixed connection with the brackets 64, which are mounted on the parts 115 57 and which carry the brake head adjusting springs 65. These springs are mounted between the downwardly directed ears 64^a of the brackets, and are secured thereto by means of rivets 66, or the like. The brake 120 heads 67, carrying the brake shoes 68 are rotatably mounted on the reduced end portions 59 of the brake beams and abut against the shoulders 59^a, formed by the ends of the parts 57. The brake heads are maintained 125

130

on the brake beams by means of brake beam keys 70, having the form illustrated particularly in Fig. 12. These keys have U-shaped slots 70^a, which are adapted to fit into the 5 annular grooves 60 at the ends of the brake beams. These keys are further provided with upward extensions 70^b, having apertures 70^c, by means of which the key is secured to the flange 67^a of the brake head by 10 means of the pins 71. In this way the brake heads are securely fixed on the ends of the brake beams without the use of nuts or other similar fastening devices, and the brake shoes are maintained in the proper positions 15 on the brake beams by means of the springs 65, previously described, which are bent at their lower ends to form the apertured ears 65^a, which are pivotally connected to the connecting members 73, shown particularly 20 in Fig. 14. These connecting members are pivotally connected at their other ends to flanges 67^a of the brake heads by means of pins 74. By means of this connection the lower end of the brake shoe is maintained 25 in contact with the car wheel when the brake shoes are moved into operative positions, and at the same time the adjusting springs 65 permit the necessary adjustment of the brake shoes to the peripheries of the car 30 wheels.

In the operation of this mechanism the movement of the operating rod 42 to the right, as viewed in Fig. 1, will first cause the lever 40^a to move about its central pivot 35 point on the adjacent member 34 until the corresponding brake shoe 68^a is moved into contact with the car wheel. This brake shoe then acts as a fulcrum whereby the continued operation of the brake mechanism 40 will move the member 34, to which the lever 40^a is connected, to the right. This movement will be permitted by the links 31 and will result in a movement of the lever 40^b until the brake shoe 68^b engages the opposite 45 site side of the inner car wheel, after which this brake shoe will act as a fulcrum, and the upper end of the lever 40^b will be moved to the right, and thereby effect the operation of the next truck lever 40^c. This truck lever 50 will operate its brake shoe 68^c, which will engage its car wheel, and then cause the carrier 34, adjacent the center wheel, to move to the right until the next brake shoe 68^d engages the car wheel. The upper end of 55 the lever 40^a then moves to the right and actuates the levers 40^e and 40^f, thereby causing the brake shoes 68^e and 68^f to engage opposite sides of the car wheel at the end of the truck. During this operation oppositely 60 disposed levers 40, adjacent each car wheel, will maintain a substantially parallel relation, and the link 31 will permit a free and efficient movement of the carriers 34, which will result in a quick action of the brake 65 mechanism and an even pressure of the brake

shoes on the various car wheels. It will be apparent that the construction of the lever mechanism and of the brake hangers permits the operation of the apparatus without interference with the spring structure. 70

An important feature of the invention is the novel means of attaching the brake heads to the brake beams, so that they are held securely and cannot be accidentally displaced, although they may be conveniently 75 removed when desired.

The means for supporting the brake beams and for mounting the brake shoes on the brake beams are described and claimed in my co-pending divisional application Ser. No. 196,831, filed October 6, 1917.

One embodiment of the invention has been shown and described for the purposes of illustration, but it will be understood that the invention may be embodied in various 85 forms without departing from its scope as defined in the appended claims.

I claim:—

1. In a railway car, a truck comprising a plurality of wheels, brake shoes suspended 90 on opposite sides and in the plane of each of said wheels to coact with the peripheries thereof, truck levers located opposite each of said wheels, connecting rods extending between said levers, and supporting means 95 located centrally opposite each of said wheels and engaging those connecting rods which extend across the axes of said wheels for supporting all of said levers and all of said rods.

2. In a railway car, a car truck, a bracket secured to said truck above one of its wheels, a lever carrier pivotally suspended from said bracket, truck levers pivoted on the opposite ends of said lever carrier, brake beams 105 connected to the lower ends of said truck levers, brake shoes carried by said brake beams, and operating connections extending to the upper ends of said truck levers.

3. In a railway car, a car truck, a supporting member carried by the frame of said truck, a pair of links pivoted on said supporting member and extending downwardly therefrom, a lever carrier pivoted to each of said links at the lower end thereof, truck 110 levers pivoted to the opposite ends of said lever carrier, brake beams suspended from said frame at opposite sides of a car wheel, brake shoes carried by said brake beams and adapted to coact with opposite sides of said 115 wheel, means for connecting said brake beams with the lower ends of said truck levers, and operating connections for the upper ends of said truck levers.

4. In a railway car, a car truck comprising a plurality of wheels, brackets secured to the frame of said truck above the axles of each of said wheels, parallel links pivoted on said brackets and depending therefrom, lever carriers pivoted to the lower ends of 120

said links, truck levers pivoted at intermediate points on the opposite ends of said lever carriers, means for operatively connecting the upper ends of said truck levers, and 5 brake shoes connected to the lower ends of said truck levers and adapted to engage opposite sides of each of said car wheels.

5. In a railway car, a car truck comprising a plurality of wheels, lever carriers pivotally suspended substantially above the axles of said car wheels, truck levers pivotally connected to the opposite ends of said lever carriers, brake beams suspended from the frame of said truck and extending on 10 opposite sides of each of said wheels, brake shoes carried by said brake beams and adapted to engage opposite sides of said wheels, means for connecting said brake beams with the lower ends of said truck 15 lever, an operating member pivotally connected to the upper end of the truck lever at one end of said truck, means for pivotally connecting the upper end of the truck lever at the other end of the truck to the truck 20 frame, and means for operatively connecting the upper ends of the intermediate truck levers.

6. In a railway car, a car truck comprising a plurality of wheels, brackets secured to the frame of said truck above the axles of each of said wheels, parallel links pivoted on said brackets and depending therefrom, lever carriers pivoted to the lower ends of said links, truck levers pivoted at intermediate 30 points on the opposite ends of said lever carriers, means for operatively connecting the upper ends of said truck levers, brake shoes connected to the lower ends of said truck levers and adapted to engage opposite 35 sides of each of said car wheels, and means for maintaining the operating surfaces of said brake shoes concentric with their respective car wheels.

7. In a railway car, a truck comprising a plurality of wheels, movable members mounted opposite each of said wheels, means

for supporting said movable members directly from the frame of said truck, truck levers pivoted on opposite ends of said movable members, brake shoes mounted adjacent the peripheries of said wheels and connected to the lower ends of said brake levers, means mounted independently of the truck frame for operatively connecting said truck levers, and means connected to one of said levers for actuating all of said brake shoes through said truck levers and movable members.

8. In a railway car, a truck comprising a plurality of wheels, a lever carrier suspended from said truck adjacent each of said wheels, truck levers pivotally mounted on said lever carriers, brake shoes pivotally connected to said truck levers and adapted to engage opposite sides of each of said 55 wheels, operating connections between adjacent pairs of said truck levers, and means connected to one of said truck levers for simultaneously actuating all of said truck levers through said lever carriers.

9. In a railway car, a car truck, a supporting member mounted adjacent a wheel thereof, a lever carrier suspended from said supporting member above the axle of said wheel, truck levers pivoted at intermediate 75 points on said lever carrier on opposite sides of said axle, brake shoes connected to the lower ends of said truck levers, and operating connections extending to the upper ends of said truck levers.

10. In a railway car, a car truck, a supporting member mounted adjacent a wheel thereof, a lever carrier suspended from said supporting member, truck levers mounted on opposite ends of said lever carrier, brake 85 shoes connected to said truck levers and adapted to engage opposite sides of the periphery of said wheel, and operating connections extending to said truck levers.

In testimony whereof, I have subscribed my name.

EDWARD POSSON.
